PROTECTED GRATE

John Moore, Brookline, Pa., assignor to Richard C. Remmey Son Co., Philadelphia, Pa., a corporation of Pennsylvania

Application September 23, 1931, Serial No. 564,534

16 Claims. (Cl. 110—33)

This invention relates to furnace grates and comprises a novel grate having its supporting or fuel-bed face protected by replaceable block units of refractory material.

It is well recognized that metallic furnace grates, and particularly those employed under boilers in industrial installations, are subjected to destructive temperature conditions which shortens the life of the grate and impair its mechanical efficiency. The defects due to warping and cracking of metallic grate bars are particularly objectionable in movable grates employed in connection with mechanical stokers since any distortion of the grate bars is likely to interfere with the required movement of the grate or the stoker parts.

I have discovered that the difficulties heretofore encountered may be largely eliminated and the life of the grate increased to a striking degree by protecting its fuel-bed face with a facing of refractory ceramic blocks or block units assembled in transverse rows, the units in each row over-lapping those in the next lower row and thus serving to hold them in place upon the bed of the grate.

It is important to secure the refractory block units detachably but reliably in place in assembling the facing and positively to prevent their displacement when the grate is moved or when fuel is delivered thereto. These objects I attain by providing an interlocking connection between the individual block units and the supporting face of the grate frame, which is designed to retain the units against separation from the supporting face and at the same time permit them to be moved parallel thereto into or out of any selected position while so retained.

It is important also that the refractory block units be so assembled in the grate that any selected unit may be removed for repair or replacement and for this purpose bolts and clamping fasteners in general have been found unsatisfactory because of the effect thereon of the heat to which they are subjected in use. With a view to overcoming this difficulty, my invention contemplates a facing of refractory block units which may be retained in operative position upon the grate by a hold-down member of simple construction but which is effective by reason of its shape and weight in preventing displacement of any units in the assembly comprising the facing. By removing the hold-down member, any longitudinal tier or row of block units is made accessible and the individual unit therein selected for

replacement may be thereupon conveniently reached.

As herein shown, I have arranged the refractory block units in transverse rows and in overlapping relation. This is not only important in securing the individual units in place upon the grate, but by properly shaping the units, transverse channels or grooves may be provided in the face of the grate which serve to retain the fuel against slipping downwardly upon the grate.

Another important feature of my invention consists in a protected grate having air passages therein by which air is admitted through the fuel bed and the efficiency of combustion thereby improved. In the construction herein shown, the supporting frame of the grate is provided with air passages and the refractory block units of the facing are also provided with air passages and are assembled upon the frame so that their air passages substantially register with those of the frame.

It is important that the air passages be of sufficient size to result in a cooling action upon the refractory facing and admit sufficient air for combustion and still be small enough in area to prevent clinkers from working into them. As herein shown, these desirable objects are accomplished by a novel arrangement of air passages or ports in the individual block units. These are arranged in relatively offset or displaced relation so that when the units are assembled, the ports in adjacent ends thereof do not symmetrically register at the fuel bed face of the units. The staggered relation of the ports thus presents no openings of substantial width although the aggregate area of the ports is amply sufficient for the requirements of the grate under all working conditions.

Accordingly, in one aspect, my invention comprises a protected grate provided with air ports having staggered or offset openings. In another aspect, it consists in a refractory block unit of novel form adapted for use in a protective facing of the character described. An important feature of such a block unit consists in air ports extending from its upper and lower face in opposite sides thereof which ports are unsymmetrically arranged so that adjacent units may be assembled with the ports in offset relation. Another feature of the novel block unit herein shown consists in the construction which includes an under-cut face at one edge of the unit and a beveled face at the other edge of the unit, the faces being so designed and proportioned that the beveled face of one unit may be over-lapping and

interlocked with the under-cut face of the next adjacent unit.

Still a further feature of the invention consists in a novel form of a refractory block unit having a curved face and being adapted for use in the lower tier or row in the grate. As herein shown, these units are arranged to retain in position the higher block units of the protective facing of the grate and are themselves retained in place by being over-lapped. For this purpose the unit is provided with a portion bounded by flat faces for interlocking engagement with an overlying block unit, and with channels or grooves in its inner face for receiving correspondingly located retaining bars or flanges.

These and other features of the invention will be best understood and appreciated from the following description of a preferred embodiment thereof, selected for purposes of illustration and shown in the accompanying drawings, in which,—

Fig. 1 is a view in perspective of one section of a protected grate with parts broken away and certain of the block units removed.

Fig. 2 is a view in perspective, on an enlarged scale, of one of the block units of the protective facing.

Fig. 3 is a similar view showing the unit in different position.

Fig. 4 is a similar view of one of the block units of the lowermost tier.

Fig. 5 is a view in end elevation, on an enlarged scale, of the hold-down member and adjacent parts, and

Fig. 6 is a view in front elevation of the hold-down member.

As herein shown, my invention is embodied in one section of a reciprocating extension grate for an underfed stoker fired boiler. This represents one of the most advantageous applications of my invention, but it will be understood that it is not by any means limited to this or to any other specific type of grate or installation.

The metallic frame of the grate includes side pieces 10 of triangular contour and an inclined bed piece 12, together with a lower cross-bar 18 and an upper cross-bar 26. The inclined bed piece 12 is provided at regular intervals across its face with longitudinal undercut or dove-tailed ribs 14 and suitably spaced between the ribs 14 are air passages 16 which extend through the bed piece and serve to admit air through the fuel bed.

At the lower forward edge of the grate frame is provided the lower cross-bar 18 and this is formed with an upstanding flange at its forward edge and with a series of short transverse ribs 20 on its upper face. The lower cross-bar also includes a vertical flange 22 standing higher than the edge flange and provided with a series of square notches 24 in its upper edge which constitute air passages corresponding to the passages 16 of the bed piece 12.

At the upper rear end of the grate is provided the upper cross-bar 26 and this is similarly provided with notches 28 in its upper edge. An elongated hold-down member 30 which may be either of cast iron or refractory material, is designed to fit with the upper cross-bar 26 and for this purpose is provided with spaced ribs 33 and 35 upon its lower face which form between them a channel of the proper dimensions to receive the cross-bar 26. The hold-down member 30 may extend from one side to the other of the grate as an integral piece or in sections and by resting upon the uppermost row of block units holds the entire assembly in place. The under side of the

upper or web portion of the hold-down member is provided with air passages 31. Elongated lugs 32 are secured to the outer face of each side piece 10 for the purpose of spacing the grate sections and preventing rubbing of the block units of one section upon those of the next or upon the adjacent main castings of the grate.

I will now proceed to describe the individual block units of the facing and then the manner in which they are assembled in the grate. The block units are preferably of silicon carbide or other suitable refractory material which may be shaped and fired as is the practice in the manufacture of ceramic articles. Each block unit 40 is rectangular in its general contour and increases in thickness from one edge to the other. The thinner edge of the unit is provided with an inclined or beveled upper surface 42, the angle of bevel being relatively acute, for example 10°, with the plane bottom face of the unit. The thicker edge of the unit is undercut to form a concealed block receiving space bounded by a face 46 which is disposed substantially at right angles to its bottom face. Above the undercut edge face of the unit is a beveled upper face 44 oppositely inclined, as compared to the face 42 and at a more abrupt angle or inclination, for example 40°. The intermediate portion of the upper face of the unit is inclined toward the thinner edge thereof as already indicated. Symmetrically disposed in the lower face of the block unit is a transversely extending groove or channel 48 with undercut side walls adapted to fit the dove-tailed ribs 14 of the bed piece of the grate.

In each end face of the unit are provided air ports which merge into a single passage opening through the bottom face of the unit but which are dissimilar in their contour above the bottom face, as seen in Figs. 1 and 2. The left-hand face of the block unit is provided with three semi-circular grooves which diverge and open through the upper surface of the unit in three semi-circular openings. The right-hand end face of the block unit, as best shown in Fig. 3, is provided with two semi-circular grooves 45 which extend upwardly in substantially parallel relation and are thus arranged in offset or staggered relation with the diverging openings in the left-hand end of the unit. In other words, the intermediate partitions between the three grooves 47 are located, in the assembled facing, opposite to the grooves 45 of the next adjacent unit. The opening of each port in the surface of the facing is thus of irregular contour, of substantial area in the aggregate, but nowhere sufficiently wide to admit a clinker.

The intermediate block units 40 of the facing are grooved at both ends as already described. The block units 41 for the outer longitudinal rows are each grooved only at one end and are provided with plane outer end surfaces.

The block units 50 and 51 of the lowermost row are also rectangular in their general contour and each has an outer cylindrical face which merges at the upper edge of the unit into a narrow flat face 52 designed to fit the undercut or lower edge face of the block units 40 and 41 in the next higher transverse row. As in the flat units, the units 50 are thicker at their lower edge than at their higher edge. The inner face of each unit is irregular in outline being provided with a lower step in which is formed a longitudinal groove or channel 56, and with a higher step in which is formed a parallel channel 58. The channel 56 is designed to fit upon the upstanding edge flange 75

of the lower cross-bar 18 and a channel 58 is designed to fit upon the higher flange 22. Both channels 56 and 58 extend vertically in the block unit and in parallel relation so that the unit may be placed upon or removed from the two flanges in a vertical direction but is held positively in position against the forward and downward pressure of the higher block units. The short ribs 20 are spaced so that they engage the end faces 10 of the units, and the end faces are notched to receive them and thus positively prevent transverse displacement thereof upon the upstanding flanges.

Each of the block units 50 is provided with air passages in its opposite end faces and, as in the flat units, these open through the curved faces of the units in staggered or offset relation. As shown in Fig. 4, the two passages 57 extend in a radial direction from a common opening in the 20 inner face of the unit to spaced semicircular openings in its outer curved face. Similar passages 55 are formed in the other face of the unit. The end unit 51 of the lowermost row is provided with air passages in one end face and has a plain 25 outer face. When the units 50 and 51 are assembled the passages in the adjacent ends form air ports of irregular contour which communicate with the notches 24 in the flange of the cross-bar 18.

In assembling the protective facing of the grate the units 50 and 51 are first placed upon the vertical flanges of the cross-bar 18 with the air passages registering as above explained and in this position they are held positively against 30 movement in all directions except directly upwardly. The block units 40 and 41, of the next row in the facing are then successively registered with the ribs 14 and slipped downwardly upon the inclined face of the bed piece 12 until they 35 rest upon and interlock with the thinner edges of the units 50 and 51. The block units 40 and 41 of the next row are similarly assembled until the entire supporting face of the bed piece 12 is covered. Finally the hold-down member 30 is placed 40 upon the flange of the cross-bar 26 and it will be seen that its lower face rests directly upon the flat inclined faces 42 of the block units 40 and 41 of the uppermost row. The whole assembly is thus locked reliably and securely in place upon 45 the grate without the use of threaded fastenings of any kind or of any fastening device except the hold-down member 30 which is of plane, flat-faced construction and not likely to become distorted under the temperature conditions to which 50 it is subjected.

The hold-down member 30 is positioned upon the cross-bar 26 by a combined sliding and rotating movement. The rib 33 of this member is relatively shallow and rounded while the rib 35 55 is provided with a rounded rearwardly extending foot, as best shown in Fig. 5. The under surface of the cross-bar 26 is curved or beveled so as to permit this foot to swing beneath it in positioning the hold-down member. It will be seen that when the latter is thus located in operative position, it cannot be displaced by direct upward pressure but must be released by a combined lifting and rotary movement.

For the purposes of replacement the facing 60 may be disassembled by following a reverse procedure.

It will be apparent from the foregoing description that I have produced a protected grate structure of long life and high efficiency both mechanically and thermally, comprising an assembly

of simple mechanical parts which may be manufactured conveniently and at low cost. The design of the refractory block units particularly favors manufacture economically and with small waste due to breakage.

Having thus described my invention, what I claim as new and desire to secure by Letters Patent of the United States is:

1. A grate for furnaces, comprising a metallic frame having an inclined supporting face, an upper facing of refractory block units arranged in transverse rows each of which overlaps the next lower adjacent row, interlocking means carried by the frame and units and acting to prevent movement of the units away from the frame without preventing movement thereof down said inclined face, and an elongated casting overlapping the uppermost row of block units.

2. A grate for furnaces, comprising a metallic frame having an inclined supporting face with a transverse retaining bar disposed along and adjacent to its lower edge, a row of refractory block units anchored upon said bar, a facing of refractory block units assembled upon the supporting face of said frame, successively overlapping each other in rows and one row overlapping said anchored units, and interlocking means carried by the frame and units and acting to prevent movement of the units away from the frame without preventing movement thereof down said inclined face.

3. A grate for furnaces, comprising a frame having an inclined supporting face with longitudinal ribs thereon, and a transverse flange with stops adjacent thereto near the lower edge of the supporting face, and a facing of ceramic blocks assembled upon said face in transverse rows, the lower row being anchored upon said flange and being held against transverse displacement by said stops, the blocks of each higher row overlapping those below and being held against transverse displacement by said ribs.

4. A grate for furnaces, comprising a frame having an inclined supporting face with longitudinal undercut ribs thereon, transverse flanges adjacent to the top and bottom edges of the frame and the frame having air passages disposed between the longitudinal ribs, a facing of refractory block units each having an air passage therein assembled upon said supporting face and upon said lowermost flange in transverse rows with their passages registering with those of said face, the lowermost row being anchored upon the lowermost flange and the units of each higher row overlapping those below it, and a removable hold-down member connected to the uppermost flange and overlapping the uppermost row of block units.

5. A refractory block of ceramic material for use in facing furnace grates, comprising a body of rectangular outline having an inclined intermediate face merging into oppositely-inclined marginal faces, said body decreasing in thickness toward one longitudinal edge and having air passage grooves in an end face which open into said intermediate face.

6. A grate for furnaces, comprising a metallic frame, an inclined supporting surface and a cross bar at its upper edge, a facing of refractory blocks arranged in tiers on the frame in overlapping relation, corresponding vertical grooves fitting said flange and being thereby held against removal except in a vertical direction, and an assembled facing of ceramic blocks upon said supporting face bearing vertically upon said lower row of blocks in a manner to hold them in place

upon the flange, each block being engaged with said supporting face so that it may be moved only in a direction parallel thereto.

7. A grate for furnaces, comprising a frame having an inclined supporting face and a flange at its lower edge, a lower row of ceramic blocks anchored upon said flange, means for positively preventing transverse movement of the blocks along the flange, and an assembled facing of 10 ceramic blocks slidably interlocked with the supporting face and resting upon said anchored blocks in such manner as to hold them in place upon the flange.

8. A grate for furnaces, comprising a metallic frame having an inclined supporting face with dove-tailed ribs thereon extending toward its lower edge, a transverse flange adjacent to said lower edge, and a facing of ceramic block units assembled in rows upon said face, the lowermost 15 row thereof being anchored upon said flange and the units of each successive higher row being arranged to slide downwardly on the supporting face while engaged by said ribs into overlapping relation with the units of the next lower adjacent row.

9. A grate for furnaces, comprising a frame having an inclined supporting face with spaced undercut ribs and intermediate air passages, and a facing of ceramic blocks each shaped to engage the ribs and slide downwardly on said supporting 20 face while so engaged and each individually having a part of an air passage therein, said blocks being assembled upon the supporting face with their passages registering with those of the supporting face and in interlocking relation with 25 said ribs.

10. In a protected grate for furnaces, a frame having an inclined supporting surface and a cross bar at its upper edge, a facing of refractory blocks arranged thereon in overlapping relation in tiers, a hold-down member shaped to overlie the uppermost tier of blocks and having downwardly projecting ribs upon its lower face spaced to straddle said cross bar, one of said ribs having 40 a laterally projecting portion adapted by a turning movement of the hold-down member to be located beneath said cross bar in interlocking relation therewith.

11. A ceramic refractory block unit adapted to 45 be positioned upon an inclined frame in a furnace grate and comprising a body of substantially rectangular outline increasing in thickness from its upper toward its lower edge, having its thicker edge undercut to provide a covered space bounded by a concealed edge face, whereby in the grate 50 it may overlap another block unit having a thick-

ness equal to its own thinner edge, and having also an undercut groove in its bottom face disposed at right angles to its lower edge.

12. A block unit as defined in claim 11, further characterized by the fact that, as positioned upon the grate frame, the upper and lower marginal portions of the upper surface of the block unit are inclined at different angles with respect to the intermediate portion thereof.

13. A refractory block unit of ceramic material 10 adapted to be positioned upon an inclined frame in a furnace grate and comprising a body of substantially rectangular outline having air passage 15 grooves in its opposite ends which are arranged respectively in offset relation to each other, and in such manner that units may be assembled in adjacent relation in straight horizontal tiers on the frame with said grooves disposed in staggered relation.

14. A refractory block unit of ceramic material 20 adapted to be secured in position upon an inclined frame in a furnace grate and comprising a body of substantially rectangular outline having in one end a groove branching upwardly into three 25 openings through the surface of the unit and in the other end a groove branching into two openings disposed out of line with those in the end first mentioned and in such manner that the openings are staggered in adjacent units as assembled.

15. A refractory block unit of ceramic material 30 adapted to be secured in position upon an inclined frame in a furnace grate and when so secured having a cylindrical outer face merging at its upper margin into a plane face and having 35 grooves in both ends of the block extending radially with respect to said cylindrical face and opening through said face in locations offset at opposite ends with respect to each other and in such manner that the openings are staggered in 40 adjacent units as assembled.

16. A ceramic refractory block unit adapted to be located on a downwardly-sloping frame in a furnace grate, being substantially rectangular in its general outline and having three surfaces on 45 its upper face, the surface adjacent to the upper edge of the block as it is positioned on its frame being substantially horizontal, the second and intermediate surface having a slight downward slope and the third sloping downwardly abruptly 50 and being undercut to provide a block receiving space bounded by a concealed edge wall, and said block having in its bottom a dove-tailed groove which extends at right angles to the surface division of its upper face.

JOHN MOORE.
